MICA SORTING MACHINE

Filed Feb. 23, 1927

FIG. 1.

FIG. 2.

INVENTOR
LOUIS T. FREDERICK

By Cheever & Cox
ATTYS.

UNITED STATES PATENT OFFICE

LOUIS T. FREDERICK, OF VALPARAISO, INDIANA, ASSIGNOR, BY MESNE ASSIGNMENTS, TO CHICAGO MICA COMPANY, OF VALPARAISO, INDIANA, A CORPORATION OF INDIANA

MICA-SORTING MACHINE

Application filed February 23, 1927. Serial No. 170,203.

My invention relates to a method and apparatus for sorting mica laminæ, and particularly for sorting the light flakes from the heavier flakes so that the former may be collected and used for the manufacture of mica plate and other commodities. The object of my present invention is to provide an improved method and apparatus for sorting mica flakes by means of a combined tumbling and blowing operation. Other objects of my invention reside in providing a device wherein the intermixed light and heavier mica flakes and air blast are introduced into one end of an inclined mica lifting drum, and preferably in a tangential manner, so that the desirable light mica laminæ will be more effectively separated from the heavier flakes, the lighter flakes being blown out of the opposite end of the tumbling drum and the heavier flakes gravitating toward and being discharged from the inlet end; to provide a sorting apparatus having a drum rotatable in inclined position and formed with conical walls forming a restricted outlet which not only more effectively permit the lighter flakes to be blown therethrough, but also, by reason of the inclination of the conical walls, prevent the heavier flakes from being blown through this outlet and thereby permit them to gravitate rearwardly through the tumbling barrel for collection; to provide a more improved manner of introducing the mica laminæ and air blast into the tumbling barrel, and to provide an improved construction for separating the dust from the lighter flakes at the discharge end of the tumbling drum.

I obtain these objects by the apparatus illustrated in the accompanying drawing, in which—

Figure 1 is an elevation of the apparatus with certain parts in section.

Figure 2 is a section on line 2—2 of Figure 1.

Like numerals denote like parts throughout the several views.

In the particular embodiment of my invention illustrated I provide a support composed of upstanding members, the forward

member 10 being higher than the rear member 12 so that the tumbling drum or barrel 14 will be supported in inclined position. These upstanding members are provided on their upper portions with friction rollers 16 which have inwardly converging sides or are formed with centrally disposed circumferential slots 18 adapted to receive a circumferential outstanding flange or web 20 on each end of the drum. The peripheral faces of the friction rolls on each side of the slot roll on and frictionlessly support the rotatable drum. Intermediate the webs 20 the outer face of the drum is formed with a circumferential band 22 adapted to receive the belt 24 connected to the power pulley 26. This belt is held tight by the belt tightening device 28 as is well known. In this manner the power rotates the inclined tumbling barrel.

The drum is provided with a plurality of baffles 30, the same being fixed to the inner walls of the drum and extending longitudinally from the lower inlet end to the upper discharge end. These baffles lift the intermixed light and heavier mica laminæ or flakes as they are fed into the lower end, carry them upwardly and dump them again downwardly as the drum rotates. My invention contemplates subjecting the intermingled light and heavy flakes as they are lifted upwardly and dumped from the top of the drum to a blast of air whereby the light, falling flakes will be blown longitudinally of the drum and out through its discharge opening at the opposite end and whereby the heavy flakes will fall down onto the drum and will gravitate rearwardly and be discharged. This combined lifting and blowing of the flakes has an ancillary tendency to separate loosened or incompletely separated light flakes from the heavier flakes so that as a result of the continuous lifting and dumping and blasting of the flakes substantially all of the light flakes will be separated from the heavier ones and can be collected for use.

In the present embodiment of my invention I introduce the mica directly through the air blast pipe thereby not only eliminat-

ing an extra opening in the end of the rotating drum but also permitting the mica laminations to receive a preliminary air blast treatment while passing through the air blast pipe. To carry this out I provide the inlet or lower end of the drum 14 with a stationary head 31 supported in any desirable manner, and provide this head with a substantially central opening through which passes the combined mica-feed and air blast pipe 32. This pipe terminates in a nozzle extending in a direction so as to blow the mica laminations in a direction substantially tangentially of the drum, the end of the nozzle being arranged just at the lowermost end of the drum 14 so that the mica will travel the entire length of the drum before passing through the opposite discharge end. In this manner the complete, effective length of the drum and of its baffles is used for lifting the mica flakes and for blowing the light flakes through and out of the drum. The lowermost part of the head 31 is provided with a cut-out portion 34 opposite the rotating inner wall of the drum so that the heavier mica laminae are discharged through this lower end into the receptacle 36 or to any other receiver, such as a traveling belt arranged to reconvey these unseparated portions back to a station for a further splitting treatment. The blast pipe 32 is formed with a damper or valve 38 and a connection to the blower 40, driven from a belt 42. And in addition the air blast pipe is formed with a branch pipe 44 having an open hopper 46 into which the mica is introduced from the splitting apparatus. In this manner the flakes will be blown by the blower 40 through the air blast pipe 32 through the nozzle into the tumbling drum 14.

The discharge end of the drum is of special construction. It is preferably provided with conical walls 48 forming a central restricted outlet 50 through which the lighter mica flakes are blown. By the time the flakes have travelled the length of the drum while being subjected to the combined tumbling and blowing operations, the desirable light flakes will be blown through the outlet 50. The conical walls 48 aid in retarding the heavier flakes from being blown out with the lighter ones and also serve to restrict the outlet of the drum and thereby create a more positive air pressure at this end to insure the discharge of the lighter flakes.

The lighter flakes will be blown directly against the screen 52 and will fall down into compartment 54 where they can be collected. The screen effectively blocks the passage of the flakes and permits any dust to pass through it into compartment 56 where it can be removed through outlet 58, or can be sucked through the pipe 60 connecting to the inlet side of the blower.

I have found that a device constructed in accordance with the foregoing disclosure is very efficient, has a large capacity and effects the separation of the mica in minimum time. The arrangement of the combined air blast inlet and mica inlet pipes is especially advantageous since it permits a construction with the minimum parts in the smallest available space. It also provides a preliminary blast for the mica pieces prior to their introduction into the drum so that any relatively loose or partly loosened lighter flakes are completely separated from the heavier flakes. So, also, the manner of introducing the mica tangentially into the drum where it is forced directly against the rotating baffled wall of the drum assists materially in separating the desired lighter flakes. In addition by regulating the blast through the blower pipe any degree of separation or sorting may be secured, and, further, by regulating the speed of rotation of the lifting drum a further control of the sorting operation may be effected.

Attention is called to my copending application filed August 16, 1926, Serial No. 129,374.

Having thus described my invention, what I claim as new and desire to secure by Letters Patent is:

1. In a machine for sorting mica flakes, an inclined drum, means for rotating the drum, a blower for blowing mica flakes through the drum from the lower end, a compartment into which the flakes from the drum discharge are blown, a screen in said compartment for catching the flakes and for passing the dust, and a suction pipe in said compartment in the rear of the screen, said pipe being connected to the inlet of the blower.

2. In a machine for sorting mica flakes, a drum rotating on a horizontally inclined axis and means for blowing unsorted mica flakes into the lower end of the drum, said drum having longitudinal ribs formed internally thereof whereby to lift and drop the mica flakes introduced into the drum, said blowing means being adapted to discharge the lighter flakes from the upper end of the drum, a screen arranged in the path of said mica flakes for catching the flakes and passing any dust which may be mixed therewith, and means for creating a suction to assist in drawing the dust through said screen.

3. In a machine for sorting mica flakes, an inclined drum, means for rotating said drum, means for blowing mica flakes through the drum from its lower end and for discharging the lighter of said flakes from the upper end of the drum, a screen arranged in the path of discharge of said lighter flakes for catching the flakes and

passing the dust, and means for creating a suction through said screen.

4. In a machine for sorting mica flakes, in combination, an inclined tumbling drum having a conical extension at its upper end, means for rotating the drum about its longitudinal axis, means for blowing unsorted mica flakes into the lower end of the drum and against a lateral wall thereof, said blowing means being capable of discharging the lighter flakes through the conical extension at the upper end thereof, and being incapable of so discharging the heavier flakes, means permitting the heavier flakes to gravitate from the lower end of the drum, a screen arranged in front of the upper open end of the drum for retaining the flakes discharged from the upper end of the drum while permitting the passage of dust with which the discharged flakes may be mixed.

5. In a machine for sorting thin flake like material into grades of predetermined thickness, a drum rotating on an inclined axis, an air blast for blowing unsorted thick and thin flakes into the lower end of the rotating drum, said air blast being regulated to carry the flakes of a desired thinness out through the upper end of the drum, while the thicker flakes remain in the drum and gravitate to the lower end thereof against the force of the air blast because of the rotation of the drum.

6. In a machine for separating relatively thin flake like material into grade having a desired thickness, an elongated drum open at both ends and mounted for rotation on an inclined axis, means for rotating the drum, means for blowing unsorted flaked material of various thicknesses into the drum, said blowing means being regulated so as to carry the thinner flakes, having a desired weight per unit of area, out through the upper end of the drum, while permitting the thicker flakes having more than the desired weight per unit of area to remain in the drum, whereby the rotation thereof will cause said thicker flakes to gravitate gradually to the lower end thereof, said drum being provided with internal projections whereby the flakes will be tumbled about therein and subjected repeatedly to the action of the blowing means in order that all of the flakes of a predetermined thinness may be separated.

7. In a machine for separating relatively thin flake like material into grades having a desired thickness, an elongated drum open at both ends and mounted for rotation on an inclined axis, means for rotating the drum, means for blowing unsorted flaked material of various thicknesses into the drum, said blowing means being regulated so as to carry the thinner flakes, having a desired weight per unit of area, out through the

upper end of the drum, while permitting the thicker flakes having more than the desired weight per unit of area to remain in the drum, whereby the rotation thereof will cause said thicker flakes to gravitate gradually to the lower end thereof, said drum being provided with internal projections whereby the flakes will be tumbled about therein and subjected repeatedly to the action of the blowing means in order that all of the flakes of a predetermined thinness may be separated, said drum being formed with a restricted opening at its upper end whereby to more thoroughly retain the thicker flakes in the drum.

In witness whereof, I have hereunto subscribed my name.

LOUIS T. FREDERICK.
